UNITED STATES PATENT OFFICE.

SIMON E. SCHROEDER, OF NEWTON, IOWA.

WASHING-MACHINE TUB.

Application filed February 6, 1925. Serial No. 7,226.

My invention relates to washing machine tubs. The invention has special reference to the construction of the tub from metal, and in its formation the utilization of the material of the metal shell to provide baffle members, viz, the impressing from the metal body, the necessary and required baffles.

The invention includes the fashioning of a tub including baffle members, without the necessity of attaching baffle members to the interior of the shell, also the special fashioning of a top closure member from a sheet metal body adapted for union detachably with the main tub shell, and in connection with which a central clearance opening is provided.

The invention further includes the provision of an upstanding centrally disposed baffle member of novel form and construction.

The invention also includes the fashioning of baffle members in conjunction with the tub shell to provide truncated ridge members continuously extended from an initial point above the bottom of the tub and continuously extending to substantial proximity to the centrally disposed baffle member.

The invention includes a central drain means in association with the baffle member.

In a further respect, this invention provides a novel method of washing clothes in a more efficient and thorough manner than heretofore employed.

This and other features of the invention and the novel method referred to, will appear more fully in the following detailed description when read in connection with the accompanying drawings, and will be pointed out in the appended claims.

Referring to the drawings:

Fig. 1, is a vertical sectional view through the center of the tub, except that a baffle member is shown complete in full lines.

Fig. 2, is a vertical sectional view, through the center of the bottom portion of the tub and attachment members thereto, and showing a partial central sectional view of the baffle member.

Fig. 3, is a similar view to that shown in Fig. 2, except with respect to the adjustment of a movable part of the structure shown.

Fig. 4, is a top view of the tub.

Fig. 5, is a side elevation of the tub, and

Fig. 6, is a bottom view of the tub.

Referring to the drawings, 10, is a main shell preferably developed from a single

metal sheet through stamping process, said shell being preferably fashioned at its bottom central portion with the circulation depression 11, and at the center of such depression 11, and at the center of such depression with circulation opening. 12, is a plate member attached to the bottom of the tub and fashioned with a boss member for conformatory seating within the opening in depressed member 11, of the main shell. 13, 65 is a drain way opening in plate member 12, and through an extension 14, therefrom. 15, refers generally to baffle members impressed for projection within the body of the tub shell, comprising vertically and horizontally 70 extending reach portions thereof, respectively indicated as: vertical reach 16, and horizontal reach 17. The baffle members are preferably fashioned to present ridge formation consisting in an expanded base portion 75 and a contracting apex as shown.

18, is a shell which constitutes the main body of a centrally disposed baffle member, the same being seated in conjunction with case frame member 19, the latter being detachably related to the bottom of the tub by means of a threaded union thereof, with upstanding member 20 associated with or connected with bottom plate member 12. Cast member 19, is fashioned with an opening 80 as 21, adapted for entry therethrough of a stem or plunger member associated with drain means for the tub. The bottom edge of cast member 19, is arcuately recessed at spaced intervals as indicated in 21^a thereabouts to afford drain way entry means from the main body of the tub to the interior of the general combination structure. The main functioning purpose of baffle member 18, is for co-operation with the specially 85 formed baffle members to the end of producing a certain circulated action, viz, a progressive spiral course of the liquid content, progressively active throughout the interior circumference of the tub as distinguished from 100 cross currents passing through the center thereof.

A drain means is provided in conjunction with the baffle member and the bottom of the tub, comprising a plug for opening or closing drain way 13, which includes a stopper element 22, fixed to a screw plug 23, the latter threaded for projective union with member 20 of bottom plate 12. The plug or stopper member is raised or lowered 110 through the action of a stem 24, projectively related to said plug and turnable through

and by means of a cap member 25, fixed to the upper end of the stem member whereby a turning movement of the cap member respectively and in opposed directions, will effect either projection or elevation of the stopper member. A coil spring member 26, is compressively and expansively related to the stem member and the top closure plate 27, at the top of baffle member 18, whereby, normally cap member 25, will be held in closed seated relation upon the top of baffle member 18, to prevent the entry of water content of the tub.

Tub top closure member 28, is preferably fashioned on general curved lines for strengthening purposes and is provided with the necessary outer marginal formation to facilitate ready detachable union with the top edge of the main tub shell.

The top is provided with an extended central opening and in the general fashioning, the inner marginal portion of the top is down-turned substantially in the manner shown in the drawing. Within the central opening of the top closure member, a suitable closure member for said opening may be provided; however, as this closure member does not constitute any part of the present invention, such member is not shown.

The tub herein disclosed, is designed for detachable seating in conjunction with a reciprocating member whereby reciprocatory action is imparted to the tub.

We will not further extend the description over that above written with respect to the operation of the device as the invention lies only in a small degree in the matter of an operative part to wit, the drain, but generally to the fashioning of the tub and the relationing of baffle members thereon, to a centrally disposed baffle member. However, we desire to note that, because of the special formation of the baffle members to present vertical and lateral projective form and the interposition of the expanded central baffle member, as the tub is reciprocated and agitation of the water content is developed therein, a progressive spiral activity of such water content is produced that causes the materials to be washed, to be continuously

moved in a progressive spiral line throughout a circular course about the central baffle member, thereby preventing the clothing from collecting at the center or any part of the interior of the tub; preventing the clothes from intertwine; and likewise, causing garments being washed therein to be extended to present the largest possible surface exposure to the water content, thereby greatly facilitating and hastening the washing action.

What I claim is:

1. In a washing machine tub comprising a sheet metal body, a plurality of spaced baffle members integral with said body, each of said baffle members comprising a vertically extending reach member and a horizontally extending reach member impressed inwardly from the side and bottom of the body respectively, a conical baffle member centrally disposed within said body and projecting upwardly to a point adjacent the upper portion of the tub, and a top for said body extending inwardly from the upper edge thereof a distance sufficient to cover the vertically extending reach members. 70

2. A washing machine tub having a metallic body and a plurality of spaced baffle members within said body, each of said baffle members comprising a vertically extending reach member and a horizontally extending reach member, said reach members having an expanded base portion and a contracted apex, and the external or working surface of said baffles being substantially continuous. 80

3. A washing machine tub comprising a sheet metal body and a plurality of spaced baffle members formed within said body and integral therewith, each of said baffle members comprising a vertically extending reach member and a horizontally extending reach member impressed from the side and bottom of the body, the sides of the baffle members converging away from the wall of the body and connected by a rounded edge, the working surfaces of each of said baffle members being substantially continuous. 90

In testimony whereof I affix my signature.

SIMON E. SCHROEDER.
